(57) **CLAIM**

The ornamental design for an elevated garden unit, as shown and described.

DESCRIPTION

FIG. 1 is a top perspective view of an elevated garden unit, showing my new design;

FIG. 2 is a top, exploded perspective view thereof;

FIG. 3 is a bottom, exploded perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is a bottom plan view thereof, with the stand portion not shown for ease of disclosure;

FIG. 11 is a cross-section view thereof, taken on line 11-11 of FIG. 8; and,

FIG. 12 is a cross-section view thereof, taken on line 12-12 of FIG. 8.

The broken lines depict environmental subject matter only and form no part of the claimed design.
